UNITED STATES PATENT OFFICE.

HENRY AVERY, OF HARTFORD, CONNECTICUT.

SURFACE-GAGE.

SPECIFICATION forming part of Letters Patent No. 267,660, dated November 21, 1882.

Application filed August 31, 1882. (No model.)

To all whom it may concern:

Be it known that I, HENRY AVERY, of Hartford, in the county of Hartford and State of Connecticut, have invented certain new and useful Improvements in Surface-Gages; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to what are known as "surface-gages;" and the object of my invention is to provide a better and readier means for adjusting the finger or pointer to a desired height, and also to provide a clamping device for the pointer, which shall not have the defect of loosening the screw when the pointer is turned in a vertical arc.

In the accompanying drawings, illustrating my invention, Figure 1 is a view in elevation of my improved surface-gage. Fig. 2 is a view at right angles to Fig. 1. Fig. 3 is a view of the lower part of Fig. 2, with the base in section, in order to show the interior parts. Fig. 4 is a horizontal section through the clamping device. Fig. 5 is a detail, which will be described.

A is the base.

B is the standard.

C is the pointer.

D is the clamp-band, which can move up and down upon the standard and be secured in any position. It carries the pointer and fixes its height.

E is a hollow cylindrical sleeve, which is pierced with a hole through its sides, in which the pointer C rests.

F is a collar which lies between the pointer and the side of the band D. It has semicircular notches, in which the pointer rests and moves with it and the sleeve E. The sleeve E passes through the collar F and enters a socket in D, in which it can turn freely. G is the clamp-screw. Its head lies within the sleeve E, and its shank, provided with a screw-thread, passes through the bottom of E, and also through the outer ends of the band D, which is split so that it can be compressed by the screw to bind the standard B. H is a thumb-

nut fitting the screw G, and bearing upon the side of the band D. This nut serves to bind the two ends of the band D together to clip the standard. The head of the screw G bears in the sleeve E, which rests in a socket in one part of D, and the shank of the screw passes through the other part of D, so that turning up the nut brings the two parts together.

J is a pin which passes through D, and through a slot cut in the shank of the screw G, to prevent the screw from turning. The arrangement of parts above described permits the pointer to be turned, together with the sleeve E and collar F, without turning and loosening the screw.

K is a circular cam, having an inclined upper surface making one complete turn around the standard B. It is furnished with a projecting flange, K', for turning it by hand, which extends a little out from the top of the base A and rests upon it. Under the flange is a conical projection, which rests in a conical seat in the base and serves as a center upon which the cam turns. The standard B passes through the middle of the cam K and extends downward through the base.

L is a cross-bar at the foot of the standard B, to which it is firmly attached. This cross-bar slides up and down upon the pins M, fixed in the base to hold the standard from turning when the cam is operated.

N is a spring, acting upward against the base A and downward upon the bar L, to hold the standard down upon the cam K.

O is a pin in the standard, which rests upon the top of the cam, and is held in contact with it by the spring N.

The operation of my invention is as follows: When it is desired to set the pointer at a given height above the base the thumb-nut H is released just sufficient to allow the pointer to turn and the clamp to slide up and down upon the standard. The end of the pointer is then turned so as to set it at the desired height, or as near it as can be readily done. It is then again clamped, and a fine adjustment given to the pointer by means of the cam K, which is operated by turning the flange K'. The cam K presses upward upon the pin O, and moves the standard against the spring N. If the cam is turned so as to lower the standard, the spring draws it down.

My invention admits of a ready and easy means for determining the distance moved up or down by the pointer. The cam K is provided with graduations 1 2 3 4, &c., as shown in Fig. 5, which show equal increments in the height of the cam, and the cam being moved a certain distance around under the pin shows the height it is raised. The pin O is provided with a line or index upon its end, to indicate

exactly its position.

What I claim as my invention is—

1. The loose sleeve E, the collar F, the screw

G, provided with a slot and pin, J, and the nut H, in combination with the band D, the standard B, and the pointer C, substantially as described.

2. The combination of the cam K, the standard B, provided with the pin O and the cross-bar L, the base A, provided with the guides M, and the spring N, substantially as described.

HENRY AVERY.
